CAN HOLDER

Jerry I. Weiss, 1333 Coral Way, Miami, Fla.

Filed Aug. 19, 1963, Ser. No. 76,270

Term of patent 14 years

(Cl. D44—21)

Fig. 3

Fig. 1

Fig. 4

FIG. 1 is a front elevational view of a can holder showing my new design, with a conventional can being shown in broken lines for purposes of illustration only; FIGURE 2 is a side elevation view of the can holder; FIGURE 3 is a top view of the can holder; and FIGURE 4 is a bottom view of the can holder.

I claim:

The ornamental design for a can holder, as shown and described.
